LUBRICATING DEVICE FOR SEWING MACHINE LOOP-TAKERS

Walter Myers, Bridgeport, Conn., assignor to The Singer Manufacturing Company, Elizabeth, N. J., a corporation of New Jersey

Application December 28, 1936, Serial No. 117,712

3 Claims. (Cl. 112—256)

This invention relates to devices for supplying lubricant to thread-case raceways of sewing machine loop-takers, and more particularly loop-takers of the vertical-axis rotary hook type, the invention having for its primary object to provide means for so controlling the quantity of lubricant supplied to the loop-taker raceway as to insure that said raceway is sparingly but adequately lubricated.

With the foregoing and other objects in view, as will hereinafter appear, the present invention consists in the loop-taker raceway lubricating device described in connection with the accompanying drawing, which illustrates a preferred embodiment of the invention and in which:

Fig. 1 represents, in side elevation, a vertical axis rotary hook having an open-top thread-case, and illustrates fragments of the needle, throat-plate and feed-dog of a sewing machine containing the present improvement. Fig. 2 represents a top plan view of the rotary hook shown in Fig. 1, the thread-case journaled in the hook being shown in horizontal section and the bobbin being omitted. Fig. 3 represents a vertical section of the hook and thread-case, the section being taken substantially on the line 3—3 of Fig. 2 and including the thread-bobbin. Fig. 4 represents in perspective and partly in section the rotary hook having an open-top thread-case.

Fig. 5 represents a sectional view similar to Fig. 3 but showing the improvement as embodied in a rotary hook having a capped thread-case. Fig. 6 represents, in perspective and partly in section, the rotary hook having the capped thread-case.

Referring more particularly to Figs. 1 to 4 inclusive of the drawing, the present improvement has been embodied in a sewing machine having the usual throat-plate 1 provided with a feed-slot 2, through which feed-slot operates a feed-dog 3 having a needle-aperture 4. The usual vertically reciprocatory needle 5 cooperates with a loop-taker 6 disposed below the throat-plate, the loop-taker shown being of the vertical-axis rotary hook type. As illustrated, the loop-taker 6 has a cup-shaped body of which the cylindrical side wall is partly cut away to provide a thread-loop seizing beak 7, said loop-taker being carried by a vertically disposed shaft 8 which may be rotated by any usual or suitable means.

The inner face of the side wall of the loop-taker body is circumferentially recessed to provide an annular raceway 9. Journaled in the raceway 9 is a bearing-rib 10 extending circumferentially about the cylindrical side wall 11 of an open-top thread-case having a bottom wall 12. Disposed

within this thread-case is a thread-bobbin 13 confined by a latch-member 14, said latch-member being pivotally supported by a bobbin-post 15 arising from the bottom wall 12 of the thread-case. In its closed position, the latch member 14 overlies the upper flange of the bobbin 13 and overhangs the rim of the thread-case wall 11 in the usual manner.

The thread-case bearing-rib 10 is interrupted to provide a thread-clearance gap between the bearing-rib ends which form opposed shoulders 16 and 17. The bearing rib 10 is confined in the loop-taker raceway 9 by a gib 18 secured by screws 19 upon the upper edge or rim of the loop-taker body, said gib 18 defining a segmental and removable portion of the loop-taker raceway. The rim of the thread-case side wall also has a nose 20 extending between stop-lugs 21 (only one of which is shown) at the under side of the throat-plate 1, whereby the thread-case is restrained against rotation with the loop-taker. The usual thread-tension spring 22 is secured by screws 23 upon the side wall 11 of the thread-case, said spring functioning to impose a frictional drag upon the thread leading from the bobbin 13.

From the foregoing brief description, it will be noted that the loop-taker and the thread-case represented are of conventional form as to details of construction.

The loop-taker 6 performs two rotations for each complete reciprocation of the needle 5 and, accordingly, at high speeds of operation of the machine it becomes necessary to lubricate the bearing of the relatively stationary thread-case. While the quantity of lubricant supplied to said bearing must be adequate to obviate friction-induced overheating of the parts, an excess of lubricant is objectionable because of attendant soiling of the needle-thread loops successively cast about the thread-case by the loop-taker. Therefore, the difficulty presented is not, primarily, to supply lubricant to the thread-case bearing but rather to so control the lubricant that there is supplied a minimum quantity adequate to meet requirements.

According to the present invention, a pad 24 of suitable lubricant-absorbent material is held against the outer face of the side-wall 11 of the thread-case by a strap 25, secured at its opposite ends, by screws 26, to said side wall so as to lengthwise extend circumferentially of said wall directly above the level of the gib 18 and preferably below the rim of the thread-case side wall. Between its ends, the strap 25 is bent outwardly away from the side wall 11 sufficiently to re-

ceive the pad and, nevertheless, to be within the path of travel of the side wall of the loop-taker 6 at the base of the beak 7. The lower edge of the pad is preferably held spaced slightly above the bearing rib 10 and also clear of the gib 18, thereby to obviate glazing of the pad by frictional contact, gib-clearance for the pad being provided in the present case by beveling the inner edge 18' of the gib 18.

10 Figs. 5 and 6 of the drawing illustrate a capped thread-case provided with the present improvement, this type of thread-case having a shallow cup-shaped base-section 27 which is outwardly flanged at its rim to provide a bearing rib 28 journaled in the loop-taker raceway, said bearing rib having the usual loop-arresting shoulder 28'. Rising centrally from said base section is a tubular post 29 for a thread-bobbin 30, the upper end of said post pivotally supporting a spring-pressed latch-member 31 serving to secure the cap-section 32 of the thread-case in bobbining position. The cylindrical side wall 32' of the cap-section has its rim fitting an annular recess 33 in the rim of the base-section 27, whereby the thread-bobbin is completely enclosed by the thread-case sections. The pad 24 and its securing strap 25 are disposed exteriorly of the cap-section 32 in the same relationship of the parts as has been described in connection with the 30 open-top thread-case.

It will be observed that the strap 25 has opposed side edges spaced from the cylindrical side wall of the thread-case, whereby the strap is open both at the top and at the bottom thereof so as to expose the upper and lower portions of the pad 24. Lubricant may therefore be conveniently supplied to the upper portion of the pad. Should the temperature of the side wall of the thread-case start to rise because of bearing friction, the viscosity of the lubricant is lessened and said lubricant thereupon gradually seeps down from the pad 24 along the outer face of the thread-case and upon the thread-case bearing rib 10, or 28. The seepage of the lubricant is slow because of the lubricant-holding nature of the pad 24, so that the lubricant is thereby controlled to sparingly lubricate the bearing rib. However, the quantity of lubricant thus supplied is adequate to meet requirements.

40 The pad 24 and its holding strap 25 are preferably so disposed circumferentially of the thread-case as to insure that the thread-loop cast about the thread-case cannot contact the pad. As illustrated in the drawing, the pad 24 is disposed 45 beyond the bearing-rib shoulder 16 at the loop-spreading side of the loop-taker and substantially

medianly between the needle-thread loop-seizing position of the beak 7 and a point diametrically opposite thereto. As will be understood by those skilled in the art, the inner limb of the thread-loop seized by the loop-taker beak 7 is engaged 5 by the shoulder 16, or 28', and is thereby restrained against being carried into contact with the pad 24 or its holding strap 25. The upper portions of the pad 24 and its strap 25 are substantially at the level of the loop-taker rim at the 10 base of the beak 7, and consequently the outer limb of the thread-loop is also guarded against contacting said pad and strap.

Having thus set forth the nature of the invention, what I claim herein is:—

15 1. A rotary loop-taker for sewing machines, comprising a cup-shaped body provided with a thread-loop seizing beak and with an annular thread-case raceway, a thread-case having a cylindrical side wall provided with a circumferential bearing-rib journaled in said raceway, a pad-holding strap upon the outer face and lengthwise extending circumferentially of said cylindrical wall of the thread-case, said strap having opposed side edges spaced from said cylindrical wall, and a lubricant-absorbent pad secured against the outer face of said cylindrical wall by said strap.

20 2. A rotary loop-taker for sewing machines, comprising a body provided with a needle-thread-30 loop seizing beak and with an annular raceway, a thread-case having a cylindrical side wall provided with a circumferential bearing-rib journaled in said raceway, a pad-holding strap detachably secured upon the outer face of said wall in spaced relation to said bearing-rib, said strap having opposed side edges spaced from said cylindrical wall, and a lubricant-absorbent pad interposed between said strap and said outer face of the thread-case wall.

3. A vertical-axis rotary loop-taker for sewing machines, comprising a body provided with a needle-thread-loop seizing beak and with an annular raceway, a segmental gib detachably secured upon said body and defining a portion of 45 said raceway, a thread-case having a cylindrical side wall provided with a circumferential bearing-rib journaled in said raceway, a pad-holder disposed upon the outer face of said cylindrical wall entirely above the horizontal plane of said 50 gib, and a lubricant-absorbent pad secured by said pad-holder against the outer face of said cylindrical wall above and in spaced relation to said bearing rib.
